J. F. ORLANDO

INDICATING FUSE PLUG

Filed May 1, 1926

FIG. 2.

FIG. 3.

Sennett Scammon
Attorneys

UNITED STATES PATENT OFFICE.

JOSEPH FRANCIS ORLANDO, OF WASHINGTON, DISTRICT OF COLUMBIA, ASSIGNOR OF
ONE-HALF TO ROBERT GLORIOSO, OF WASHINGTON, DISTRICT OF COLUMBIA.

INDICATING FUSE PLUG.

Application filed May 1, 1926. Serial No. 106,157.

This invention relates in general to fuse plugs and more particularly to a type of fuse plug comprising means for indicating the condition of the fusible element.

5 Heretofore in fuse plugs of this character there have been certain fundamental disadvantages which this invention seeks to overcome. It is a well known fact that when the fusible element of such plugs melts 10 due to the passage of an excess current, there is caused a discoloration of the transparent material, generally mica, embodied in the top or cap of the fuse, thereby obstructing the vision of the fusible element. This 15 factor has proved a particularly objectionable feature in that this discoloration is oftentimes indistinguishable from the natural discoloration or impurities frequently found in such mica. Further, fuse plugs of this character 20 have previous to this time, been of essentially different construction from the ordinary type, hence the manufacture of these fuses has necessitated a radical change in the present design and construction.

25 It is an object of this invention to provide a fuse plug embodying an indicating means whereby it may be readily ascertained whether or not the fusible element is defective.

30 Another object of this invention is to provide a fuse plug embodying an indicating means having the indicating means and the transparent material of the cap protected from the effects of discoloration caused by 35 the melting of the fusible element.

A further object of this invention is to provide a fuse plug embodying an indicating means having the indicating means so constructed as to be essentially applicable to the 40 ordinary type of fuse plug, thus precluding the need of changing the design of fuse plugs for adaptation of this invention.

With these and other objects in view which may be incident to my improvements, 45 the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accom-

panying drawings means for carrying the 55 same into practical effect, without limiting the improvements in their useful applications to the particular constructions, which for the purpose of explanation have been made the subject of illustration. 60

In the drawings forming a part of this specification:

Figure 1 is a side elevation sectional view 65 of a conventional fuse plug shown as embodying the present invention;

Fig. 2 is a top plan view thereof;

Fig. 3 is a top plan sectional view taken 70 on line 3-3 of Figure 1;

Fig. 4 is a perspective view of the component parts of the indicating device. 75

Referring by numerals to the drawings and more particularly to Figure 1, 1 is a hollow housing portion of a fuse plug of conventional construction. The wall of the housing is provided with apertures 2 and 3, 75 the aperture 2 being desired to receive one end of a fusible element 4 formed with a restricted portion, in order that there may be provided a point of high resistance on the fusible element better shown in Figure 80 4. A metal collared bushing 6 is embodied in the base of the housing, the inner collar being adapted to act as a securing means for the other end of the fusible element 4. The outer collar is designed to serve as one 85 terminal of a fuse plug.

It is preferred that this plug body be composed of one of the numerous phenol condensation products although it may be of the usual porcelain construction. 90

A portion of the outer wall of the housing is threaded thereby being adapted to receive a threaded metallic sleeve 5 to act as a securing means for the plug and as the other contact thereof having contact with the other 95 end of the fusible element 4 projecting through the aperture 2.

To the top of the housing 1 is secured in the usual manner a cap 7 provided with a rectangular aperture 8 and interposed therebetween, a disk of transparent material 9. 100

On the fusible element 4 at the point of the greatest resistance is secured a member 10 forming one of the novel elements of this invention, comprising a clamp portion 11 and a cylindrical channeled member 12 more fully shown in Figure 4. The clamped portion 11 is adapted to be clamped on the fusi-

ble element at the point of the greatest resistance. A flexible strip member 13 having designations thereon in respect to the condition of the fusible element is secured by the 5 channeled portion 12 of the member 10.

The flexible strip member 13 preferably composed of any suitable rugged fabric tape and impregnated with any non-inflammable substance is designed to be supported by an 10 elongated plate member 14 interposed between the disk of transparent material 9 and the top of the housing permitting free operation of the strip member and secured thereon by the cap 7.

15 The elongated plate member 14 is provided with an aperture 15 near one longitudinal edge thereof and disposed adjacently thereto and aligned therewith on the opposite edge, a recess 16. The aperture and the recess are preferably formed by cutting the 20 plate and bending the cut portions downward in arcuate formation better illustrated in Figure 4. The flexible tape member 13 is adapted to pass through the aperture 15 across the top of the plate over the recess 16 25 and having the opposite end held in the aperture 3 provided in the wall of the housing 1 and oppositely disposed to the aperture 2.

In Figure 3 is shown a top plan view of 30 the plate member 14 rested on the top of the housing 1 and secured thereon by the cap 7. The tape 13 having one end secured to the fusible element 4, the other to the spiral spring 20 and passing through the aperture 15 and over the recess 16.

The mode of operation of the device may be readily understood having reference to Figures 1 and 3. When the fusible element melts, it will necessarily separate at 40 the point of the greatest resistance thereby releasing the member 10. The tape portion 13 held in tension by the spring 20 will be drawn through the aperture 15 and over the recess 16 by the force of the spring. The 45 channeled portion 12 of the member 10 will act as a stop means for the tape when it reaches the aperture 15. It may be seen that the indications will thus change to denote the condition of the fusible element.

50 There is accomplished by this invention an improved indicating device adaptable to fuse plugs of conventional construction, whereby the condition of the fusible element may readily be ascertained. Further there 55 is embodied in said device the provision of a means to protect the indicating elements from discoloration resultant from the fusion of the fusible element.

While I have shown and described the 60 preferred embodiment of my invention, I wish it to be understood that I do not confine myself to the precise details of construction herein set forth, by way of illustration, as it is apparent that many changes and variations may be made therein, by those skilled

in the art, without departing from the spirit of the invention, or exceeding the scope of the appended claims.

I claim:

1. In a fuse plug embodying a fusible element, means to indicate the condition of the fusible element comprising an indicating member having a supporting means, secured to the fusible element at the point of the greatest resistance, and means to operate the 70 indicating member on a parallel plane with the supporting means comprising a spring.

2. In a fuse plug embodying a fusible element, means to indicate the condition of the fusible element comprising an indicating 80 member having a supporting means secured to the fusible element at the point of the greatest resistance and means to operate the indicating member vertically and horizontally comprising a spiral spring.

3. In a fuse plug comprising a housing of a phenol condensation product and embodying a fusible element, means to indicate the condition of the fusible element comprising an indicating member having a supporting 90 means secured to the fusible element at the point of the greatest resistance and means to operate the indicating member vertically and horizontally comprising a spiral spring.

4. In a fuse plug embodying a housing, a 95 fusible element and a transparent cap, means to protect the transparent cap from discoloration comprising a plate member interposed between the fusible element and the cap.

5. In a fuse plug embodying a housing, a fusible element and a transparent cap, the combination of a means to protect the transparent cap from discoloration and a means to indicate the condition of the fusible element comprising a plate member interposed 105 between the fusible element and the cap, the plate being adapted to support the indicating element.

6. In a fuse plug embodying a housing, a 110 fusible element and a transparent cap, the combination of a means to protect the transparent cap from discoloration and a means to indicate the condition of the fusible element comprising a plate member interposed 115 between the fusible element and the cap, an indicating means secured to the fusible element and supported by the plate member.

7. In a fuse plug embodying a housing, a 120 fusible element and a transparent cap, the combination of a means to protect the transparent cap from discoloration and a means to indicate the condition of the fusible element comprising a plate member having an 125 aperture interposed between the fusible element and the cap, an indicating means secured to the fusible element and designed to pass through the aperture provided in the plate member.

8. In a fuse plug embodying a housing, a 130

- fusible element and a transparent cap, the combination of a means to protect the transparent cap from discoloration and a means to indicate the condition of the fusible element comprising an elongated plate member having an aperture and a notch formed in alignment therewith, interposed between the fusible element and the cap, and an indicating means secured to the fusible element designed to pass through the notch and aperture provided in the plate member. 5
9. In a fuse plug embodying a housing, a fusible element and a transparent cap, the combination of a means to protect the transparent cap from discoloration and a means to indicate the condition of the fusible element comprising an elongated plate member having an aperture and a notch adjacently disposed and in longitudinal alignment therewith secured to the plug housing by the cap member and an indicating device comprising a tape member having one end secured to the fusible element, adapted to pass through the notch and aperture provided in the plate member and having the opposite end resiliently secured. 10
10. In a fuse plug embodying a housing, a fusible element and a transparent cap, the combination of a means to protect the transparent cap from discoloration and a means to indicate the condition of the fusible element comprising an indicating device comprising a tape member having one end secured to the fusible element at the point of least resistance, adapted to pass through the notch and an aperture provided in the plate member and having the opposite end attached to a spring member secured to the housing of the plug. 15
11. In a fuse plug embodying a housing, a fusible element and a transparent cap, the combination of a means to protect the transparent cap from discoloration and a means to indicate the condition of the fusible element comprising an indicating device comprising a tape having thereon desired indicators, having one end provided with a stop member secured to the fusible element the point of greatest resistance, adapted to pass through the aperture and notch provided in the plate member and having the opposite end attached to a spiral spring member secured to the housing of the plug. 20
12. In a fuse plug embodying a housing, a fusible element and a transparent cap, the combination of a means to protect the transparent cap from discoloration and a means to indicate the condition of the fusible element protected from discoloration, comprising an indicating device comprising a tape having thereon desired indicators having one end provided with a stop member secured to the fusible element at the point of greatest resistance, adapted to pass through the aperture and notch provided in the plate member and having the opposite end attached to a spiral spring member secured to the housing of the plug. 25
13. In a fuse plug a fusible element, a flexible strip including a sign, a plate member supporting the flexible strip and means for moving the flexible strip with reference to the plate member to indicate the condition of the fusible element. 30
14. In a fuse plug embodying a housing, a fusible element and a transparent cap, means to protect the transparent cap from discoloration comprising a plate member and a flexible strip interposed between the plate member and the cap. 35

In testimony whereof I affix my signature.
JOSEPH FRANCIS ORLANDO.
